DIRECTIONAL DRILLING APPARATUS

George L. Scott, Compton, Calif., and Wiley B. Noble, Houston, Tex., assignors to Reed Roller Bit Company, Houston, Tex., a corporation of Texas

Application April 3, 1939, Serial No. 265,669

14 Claims. (Cl. 255—1.6)

This invention relates to drilling equipment and has for its general object the provision of means whereby the direction in which a hole is being drilled may be changed and controlled as drilling proceeds.

In drilling deep wells, or the like, particularly by the rotary drilling method, it is frequently desirable to change the direction in which the drilling is proceeding. This may be caused either by a desire that the drilled hole be inclined or directed in a predetermined manner to reach a definite known goal, or by a desire to bring back to the vertical a hole in which the drilling has become deflected from the vertical.

Various means have been employed in the past for deflecting drilling tools so as to change or control the direction of drilled holes, most of these taking the form of so-called whipstocks or wedge-shaped blocks placed in the bottom of the well hole to deflect a drilling tool in one direction or another from the original well hole. These are objectionable for several reasons, the principal reasons being that they cause a sharp angular change in the direction of the well hole which is likely to cause trouble in subsequent operations, and that the amount of change by the use of a single whipstock is quite limited; the only way additional change can be accomplished is by the use of additional whipstocks in succession.

In all previous devices and methods of changing direction of drilling in drilled holes, there is also the disadvantage of having to withdraw the drill stem, put in place the correcting device and then again place the drill stem and drill in the hole before drilling can be continued. This is a very time consuming and expensive operation, especially in the case of wells of extremely great depths, such as are now common in many parts of the world. This operation of running the pipe into and removing it from the drilled hole may have to be repeated not once but numerous times for a single deflecting operation, thus multiplying greatly the loss of time and the expense involved.

It is an object of this invention to provide a device which will not require the use of a whipstock or the like in the well hole.

Another object of this invention is to make possible the deflection and control of the direction of a drilled hole by the use of equipment, the major portion of which is used in the ordinary well known method of drilling wells.

Another object of this invention is to provide a means for controlling the direction of drilled

holes which will avoid the necessity of round trips of the drill stem into the hole.

Another object of this invention is to provide a means whereby a drilled hole may be deflected by either a greater or a lesser amount in one deflecting operation.

Another object of this invention is to provide a deflecting device which will normally occupy a straight ahead position with respect to the drilling bit but which when deflected and drilling is begun will continue to lead the bit away from its original course, along substantially a single plane.

Other objects and advantages will become apparent from the following description taken in connection with the accompanying drawings wherein is set forth by way of illustration one embodiment of this invention.

In the drawings:

Fig. 1 is a longitudinal cross section through the upper end portion of a drill collar of an ordinary wire line coring apparatus, showing a core barrel in place therein.

Fig. 2 is a similar view showing the lower portion of the device illustrated in Fig. 1 and having a reamer and core barrel on the lower end thereof.

Fig. 3 is a view illustrating one method of orienting a drill stem and core bit such as illustrated in Figs. 1 and 2 preparatory to changing the direction of drilling in a drilled hole.

Fig. 4 is a view similar to Fig. 1 but illustrating a deflection drilling apparatus in place of the core barrel, the same being constructed in accordance with this invention.

Fig. 5 is a view similar to Fig. 2 illustrating the lower end portion of Fig. 4, together with the details of construction of the deflection drilling apparatus.

Fig. 6 is a view similar to Fig. 5 but showing the deflection drilling apparatus in use in a reamer body without a drill stem, and with the leading portion of the deflecting tool in deflected position.

Fig. 7 is a view similar to Fig. 5 but showing a modified form of the invention.

Fig. 8 is a vertical cross section showing the details of the driving element.

Fig. 9 is a fragmentary front elevation taken at right angles to Fig. 6 and illustrating the spoon shaped deflecting member.

Fig. 10 is a horizontal cross section taken along the line 10—10 of Fig. 9.

The present invention is adapted to be used in connection with that type of coring apparatus commonly known as wire line coring equipment.

In this type of apparatus, the core bit 1 having blades 2 is secured to the lower end of the drill collar 3 either with a reamer 4 positioned between the core bit and the drill collar or with the bit secured directly to the drill collar, as shown in Fig. 5.

The upper end of the drill collar is connected by means of a driver sub 5 to the tool joint 6 which is mounted on the lower end of the lowest section of drill pipe 7. The reamer 4 may be of any suitable type and may or may not be used depending upon the circumstances of the particular case. In the form illustrated, this reamer is provided with substantially vertical roller cutters 8 mounted at spaced points about its circumference and having threaded connections between its upper and lower ends for engagement with the core bit and the drill collar, respectively.

The drill collar 3 has within its upper end a driver 9 in the form of a sleeve which is carried by the lower end of the driver sub 5. This driver is provided with a notch 10 and the lower end of this notch is formed with divergent sides 11 inclined toward the notch 10 so as to guide an upwardly moving member into the notch.

In Figs. 1 and 2 a core barrel 12 is shown in place, this core barrel having a fitting 13 on its lower end with a shoulder 14 adapted to seat on a slush ring 15 mounted in the core bit. The lower end of the fitting 13 is threaded to receive the core cutter head 16 and carried within this core cutter head and clamped in place by the fitting 13 is a core catcher 17.

Mounted on the upper end of the core barrel is any suitable type of upwardly opening check valve 18, the same in this instance being mounted in a spring body 19, the major portion of which is of reduced diameter to receive a compression coil spring 20. The upper end portion of this spring body is formed with key-ways 21 adapted to receive the sliding keys 22 carried by the slip joint 23. The slip joint 23 is carried in the lower end of the sleeve 24, the upper end of which is secured to the carrier body 25. Holes 26 are provided in the sleeve to permit the inflow and outflow of fluid as the spring 20 is expanded or compressed.

The carrier body is slotted above its lower end to receive a latching dog 27, which is spring pressed in a radially outward direction by means of a spring 28 to engage beneath the lower end of the driver 9 and when moved upwardly to fit in the slot 10. This dog may be retracted by means of a pull bar 29 which is slidably mounted in the upper end of the carrier body and has a pin 30 engaging a slot 31 in the dog. The upper end of the pull bar is provided with a spear head 32 to receive an overshot which is lowered on a wire line to withdraw the core barrel from the core bit.

When drilling is going on without any core being taken the cutter head 16 is replaced with a center bit which cuts the center of the bottom of the hole.

It will be appreciated that the core barrel is placed in the core bit by simply dropping it into the upper end of the drill stem and pumping it down until it latches in place. It is removed by lowering an overshot on cable or wire line, which overshot engages the spear head 32 and the core barrel is then pulled out by withdrawing the cable.

Referring to Fig. 3 there is shown in place in the core bit a device which projects beyond its

lower end and carries a surveying instrument 33 of any well known type, which is adapted to make a record of the inclination of the bit as it rests in the hole, as well as the orientation or rotary position of the bit in the hole. Such surveying instrument is, of course, brought into a fixed orientation with respect to the bit by means of a latching dog like that used on the core barrel above described, which dog is forced into the notch 10 to rotate the instrument into proper position in the bit. Either at this time, or before the instrument is dropped into the drill stem, the drill stem is "neutralized" in order to remove rotary strains which exist in the drill pipe. That is to say, during ordinary drilling, the drill pipe will actually take on a twist amounting to several revolutions between the top and the bottom. This twist is substantially removed by rotating the drilling stem several revolutions, first to the right, then to the left in succession and gradually decreasing the amount of each rotation until a neutral position is reached.

The surveying instrument is then caused to make its record and this record when the instrument is removed will show the position of the core bit in the hole, both with respect to the vertical and with respect to north and south or some other reference point or points.

After the position of the bit has been determined, the drill stem is rotated in order to place the bit in proper orientation with respect to the direction in which it is desired to deflect a hole. For convenience the bit is usually rotated until the notch 10 faces in the direction desired. After this rotation, it is desirable that the drill stem again be neutralized in the manner above described so that there will be substantially no twist in the drill stem and the operator may be sure of the position of the bit. This process is repeated until the bit is found to be in the proper position after the pipe is neutralized. While reference has been made to rotating the bit a desired amount, it will be understood that the thing to be properly oriented is the notch in the driver rather than the bit. The bit has been referred to because ordinarily it will not change its relation with respect to the notch in the driver.

After the bit and the notch in the driver have been placed in the desired oriented position, there is then dropped into the drill stem a device illustrated in Figs. 4, 5 and 6. This device has a latching mechanism at its upper end which is similar to that shown in Fig. 1, differing only in the form shown in that the lower end of the carrier body 34 is formed with a socket for the reception of the upper end of a spring 35. This spring 35 surrounds a loose sleeve 36, the purpose of which is to limit the travel of the spring, and the spring is disposed within a sleeve 37 which is connected with the carrier body 34 at its upper end and with the slip joint 38 at its lower end. Slidably within this slip joint 38 is a packer body 39 which has key ways 40 in which keys 41 carried by the slip joint are adapted to slide. The upper end of this packer body projects through the slip joint and receives a nut 42 upon which the lower end of this spring 35 is carried.

Surrounding the packer body is a packer 43 of rubber or similar resilient material, one of the ends of this packer bearing against a shoulder 44 carried by the packer body, and the other against a shoulder 45 carried by the slip joint. It will be seen that when the packer body 39

is pushed upwardly, it will compress the spring 35 until the sleeve 36 stops the movement, and this movement will at the same time cause the shortening and expansion of the packer 43.

Secured to the lower end of the packer body is a barrel 46, and this barrel is connected at its lower end with an adapter 47 which forms a continuation thereof. Threaded onto the lower end of the adapter is a coupling 48 having a spherical seat 49 formed therein for the reception of a ball member 50. This collar at points opposite the ball member is formed with vertical slots 51 adapted to receive pins 52 which are inserted into openings in the opposite sides of the ball member to lock the ball member against rotation in the collar 48. After the pins 52 have been put into place, a sleeve 53 is dropped over the end of the coupling 48 to prevent the pins from dropping out. A tubular member 54 having a spherical seat on its lower end, is threaded into the coupling 48 to secure the ball member 50 in proper position.

The ball member is provided with a downward extension 55 having a pilot bit 56 secured to its lower end. This pilot bit is formed with a spoon-shaped lower end, the face of the spoon-shape being indicated by the numeral 57. A fluid passageway 58 is formed through the pilot bit and opens through the face thereof. At its upper end it connects with a passageway through the extension 55, the ball 50, the adapter 47 and the barrel 46. This passageway opens into the interior of the drill collar through the nut 42 and openings in the sleeve 36. It will be noted that this is above the packer 43 so that when the packer is expanded fluid pumped downwardly through the drill stem will be forced to flow through the various parts and emerge through the pilot bit 56.

Surrounding the extension 55 above the pilot bit is a coil spring 59 bearing at its upper end against a washer 60 slidably carried by the extension 55. A sleeve 61 is placed over the upper end of the pilot bit so as to surround and protect the spring 59. This spring 59 bearing against the washer 60 tends to hold the pilot bit in axial alignment with the drilling bit and the drill stem.

In Fig. 6, the device just described, is illustrated in use in a reamer body without any drill collar. For this purpose the barrel 46 is omitted and the adapter 47 is secured directly to the packer body 39. In this figure there is illustrated what takes place when weight is placed upon the tool. The tool will be deflected toward the face of the spoon shaped pilot bit as the pilot bit is forced into the formation. Thereafter, upon rotation of the drill stem, the pilot bit will keep the inclination which it has thus been forced to take and will continue to lead the main bit or deflect it in the same direction as long as drilling is continued.

In the form shown in Fig. 7, the coupling 43 and all the parts carried thereby, have been replaced by a single rigid element 62 which has the same sort of spoon shaped end 57 as that previously described. This element, however, being rigid, can be deflected only so much as the main bit may be forced into the side of the hole, and once drilling is commenced further deflection of the drilling apparatus will not take place. This form has the advantage, however, that a number of movable parts have been eliminated and it is less apt to get out of order.

In operation, when it is desired to change the 75

direction of drilling, there is first dropped into the hole a surveying instrument 33 in the manner above described. The directional drilling device, such as shown in either Figs. 5, 6 or 7 is then dropped into place and pumped down until it latches in position. When it has been properly oriented with respect to the drill, by means of the latching dog entering the notch 10, the entire drill stem is lowered to spud the projecting nose of the deflecting tool into the formation. Because of the shape of this nose, it will be deflected in the manner above described and when drilling is started, it will deflect the direction of drilling so long as drilling continues. When the desired amount of deflection has been obtained and the drill is operating in the desired direction, drilling will be stopped and the deflecting apparatus removed by means of a wire line. The center bit will then be replaced and drilling will proceed.

It will be seen from the foregoing that a means has been provided which is capable of accomplishing all of the objects and advantages sought by this invention.

Having described our invention, we claim:

1. In a device for changing the direction of a drilled hole, a drilling bit, a deflecting member carried by and projecting in advance of said drilling bit to engage the bottom of a drilled hole and deflect said bit in a predetermined direction, said deflecting member having its lower end formed in such a manner that it will be deflected in a predetermined direction upon contact with the bottom of a drilled hole and means for holding said deflecting member in non-deflected position and in rigid alignment with said bit.

2. In a device for changing the direction of a drilled hole, a drilling bit, a deflecting member carried by and projecting in advance of said drilling bit to engage the bottom of a drilled hole and deflect said bit in a predetermined direction, said deflecting member having its lower end formed in such a manner that it will be deflected in a predetermined direction upon contact with the bottom of a drilled hole, said deflecting member having a fluid passageway therethrough opening at the lower end thereof and means for holding said deflecting member in non-deflected position.

3. In a device for changing the direction of a drilled hole, a drilling bit, a deflecting member carried by and projecting in advance of said drilling bit to engage the bottom of a drilled hole and deflect said bit in a predetermined direction, said deflecting member having its lower end formed in such a manner that it will be deflected in a predetermined direction upon contact with the bottom of a drilled hole, said deflecting member having a fluid passageway therethrough opening at the lower end thereof and means for holding said deflecting member in non-deflected position and in rigid alignment with said bit.

4. In a device for changing the direction of a drilled hole, a drilling bit, and a deflecting member carried by said drilling bit and projecting in advance thereof, said deflecting member having a spoon shaped lower end, whereby upon contact with the bottom of a drilled hole said deflecting member will tend to move in the direction of the face of the spoon, said deflecting member having a fluid passageway therethrough opening at the lower end thereof.

5. In a device for changing the direction of a drilled hole, a drilling bit, a deflecting member carried by and projecting in advance of said drilling bit to engage the bottom of a drilled hole

and deflect said bit in a predetermined direction, said deflecting member having its lower end formed in such a manner that it will be deflected in a predetermined direction upon contact with the bottom of a drilled hole, said deflecting member having a fluid passageway therethrough with its outlet disposed so as to direct fluid in the direction of the deflection of said member and means for holding said deflecting member in non-deflected position.

6. In a device for changing the direction of a drilled hole, a drilling bit, a deflecting member carried by and projecting in advance of said drilling bit to engage the bottom of a drilled hole and deflect said member in a predetermined direction, said deflecting member having its lower end formed in such a manner that it will be deflected in a predetermined direction upon being forced into the formation at the bottom of the drilled hole, said deflecting member having a fluid passageway therethrough opening at its lower end in a direction toward which said deflecting member will be deflected and means for holding said deflecting member in non-deflected position and in rigid alignment with said bit.

7. In a device for changing the direction of a drilled hole, a drilling bit, and a deflecting member carried by said drilling bit and projecting in advance thereof, said deflecting member having a spoon shaped lower end, whereby upon contact with the bottom of a drilled hole said deflecting member will tend to move in the direction of the face of the spoon, and said member having a fluid passageway therethrough opening through the face of said spoon.

8. In a device for changing the direction of a drilled hole, a drilling bit, and a deflecting member carried by and projecting in advance of said drilling bit to engage the bottom of a drilled hole and deflect said bit in a predetermined direction, said deflecting member having its lower end formed in such a manner that it will be deflected in a predetermined direction upon contact with the bottom of a drilled hole and having a joint therein above the lower end for permitting such deflection without deflection of the drilling bit.

9. In a device for changing the direction of a drilled hole, a drilling bit, a deflecting member carried by and projecting in advance of said drilling bit to engage the bottom of a drilled hole and deflect said bit in a predetermined direction, said deflecting member having its lower end formed in such a manner that it will be deflected in a predetermined direction upon contact with the bottom of a drilled hole, and means yieldably urging said deflecting member downwardly within said drilling bit.

10. In a device for changing the direction of a drilled hole, in combination with a drilling bit, a deflecting member carried by and projecting in advance of said drilling bit to engage the bottom of a drilled hole and deflect said bit in a predetermined direction, said deflecting member having its lower end formed in such a manner that it will be deflected in a predetermined direction.

tion upon contact with the bottom of a drilled hole, means yieldably urging said deflecting member downwardly within said drilling bit, said deflecting means having a fluid passageway therethrough opening at the lower end thereof and means above the lower end of said deflecting member for deflecting fluid into said passageway.

5 11. In a device for changing the direction of a drilled hole, a drilling bit, a deflecting member carried by and projecting in advance of said drilling bit to engage the bottom of a drilled hole and deflect said bit in a predetermined direction, means for normally holding said deflecting member in non-deflected position in axial alignment with said drilling bit, means forming part of said deflecting member for causing said deflecting member to move to a position out of axial alignment with said drilling bit, whereby upon rotation of said drilling bit and said deflecting member, said deflecting member will continue in said position out of alignment with said drilling bit and lead said drilling bit in a path having continually greater deflection from the original drilled hole.

10 12. In a device of the character described, in combination with a drilling bit, a member carried by said drilling bit and a universal joint connecting said member with said drilling bit, said member having its forward end formed with a spoon-like shape whereby upon contact with the lower end of a drilled hole said member will be deflected in the direction of the face of said spoon and upon operation of said drilling bit it will continually lead said drilling bit in the direction of such initial deflection.

15 13. In a device for changing the direction of a drilled hole, a drilling bit, a deflecting member carried by and projecting in advance of and in substantially axial alignment with said drilling bit to engage the bottom of a drilled hole and deflect said bit in a predetermined direction, said deflecting member having its lower end formed in such a manner that it will be deflected in a predetermined direction upon contact with the bottom of a drilled hole, means for holding said deflecting member in non-deflected position and in such axial alignment, and a further means for rigidly securing said deflecting member in projecting position.

20 14. In a device of the character described comprising a member adapted to be carried by a drilling bit, means for mounting said member on said drilling bit with a portion of said member projecting ahead of the bit in normal axial alignment therewith, said member having its forward end shaped to be deflected in one predetermined direction with respect to said mounting means upon coming in contact with the bottom of a well hole, whereby upon continuing of the drilling operation said member will serve to lead said drilling bit in the direction of said deflection, and a further means for rigidly securing said deflecting member in projecting position.
